CLAIM

The ornamental design for clamping set of bracket arms for supporting tubular objects, as shown and described.

DESCRIPTION

FIG. 1 is a top three-quarter perspective view of a clamping set of bracket arms for supporting tubular objects;

FIG. 2 is a bottom plan view thereof; and

FIG. 3 is a rear elevational view thereof.

The broken line showing of a vertical mounting plate in all three figures is for illustrative purposes only and forms no part of the claimed design.

FIG. 1

FIG. 2
